UNITED STATES PATENT OFFICE.

CARLOS HOLLY, OF LOCKPORT, NEW YORK, ASSIGNOR TO F. N. BURT COMPANY, LIMITED, OF BUFFALO, NEW YORK, A CORPORATION OF ONTARIO, CANADA.

BOX.

1,174,865.

Specification of Letters Patent. Patented Mar. 7, 1916.

Application filed September 28, 1912. Serial No. 722,828.

To all whom it may concern:

Be it known that I, CARLOS HOLLY, a citizen of the United States, residing at Lockport, in the county of Niagara and State of New York, have invented certain new and useful Improvements in Boxes, of which the following is a full, clear, and exact description, such as will enable others skilled in the art to which it appertains to make and use the same.

This invention relates to boxes and box elements, and with respect to its more specific features, to boxes having collars or necks, and composed of paper, cardboard or similar flexible material.

One of the objects of the invention is the provision of a simple and efficient box of the character described, having relatively square corners both on the inside and outside of the box.

Another object of the invention is the provision of a practical box of the character described in which the corners of the collars or necks shall nicely fit the adjacent portions of the box body.

Still another object of the invention is the provision of a practical paper box of the character described in which the elements are connected by an adhesive and in which the joints in the material are concealed.

Yet another object of the invention is the provision of a blank which may be subsequently folded into a box element with its ends superposed and the joint efficiently covered.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein embodiments of the invention are shown and wherein similar reference characters refer to similar parts throughout the several views, Figure 1 is a perspective view of a blank adapted to be folded into a box collar; Fig. 2 is a view similar to Fig. 1, showing a portion of the cover material folded

onto the body material; Fig. 3 is a view showing the blank of Fig. 2 having opposite end portions folded at right angles to an intermediate portion; Fig. 4 shows a further folded condition of the blank; Fig. 5 is a perspective view showing the completely folded blank with the tongue folded within the blank; Fig. 6 is a view similar to Fig. 2, but showing the cover material extending beyond the rear edge of the blank to form a binder; Fig. 7 shows the blank of Fig. 6 partially folded around the head; Fig. 8 shows a complete box, including a collar and a cord; Fig. 9 is a section through one corner of the box of Fig. 8, taken on a line parallel to the bottom of the box below the turned in cover strip of the collar; Fig. 10 is a view of a modified form of blank; Fig. 11 is a perspective view of a complete box showing the blank of Fig. 10 folded into a collar and inserted in the box body, the joint being located at the corner of the box; and Fig. 12 is a perspective view of a box body.

The main features of this application are disclosed in applicant's contemporaneously pending application, filed January 16, 1911, Serial No. 602,862, to which reference is made, and certain aspects of the invention disclosed herein are disclosed and claimed in applicant's application filed September 3, 1910, Serial No. 580,464.

In paper boxes of the character referred to, and especially in the smaller boxes such as used for packaging cigarettes, etc., it is desirable to produce an article presenting an attractive appearance, and one which utilizes as much space as possible for the contents. Uniformity of outline and symmetrical disposition of outside parts may be ordinarily required in all boxes, and approximation of these results has not heretofore been achieved without the sacrifice of desirable features on the inside. Moreover, lack of efficient disposition of the parts or elements on the interior of a box not only often results in the appropriation of space which might be utilized for the contents of the box, but often manifest themselves on the outer surface, especially when the box is made of relatively soft material, such as varieties of paper, etc. The elements of the box of the present invention

are designed to present a nice appearance, and to take up a minimum of space consistent with their character, and to be associated in the production of complete boxes 5 avoiding the objections above noted.

In the preferred embodiment of the invention, as illustrated, the boxes are of a polygonal rectangular or prismatic form, and it will be apparent that though different forms of complete boxes are disclosed, yet the invention, viewed in some aspects, manifests itself in parts of a box of either form disclosed, or other forms.

The preferred type of box in which the invention is embodied is one comprising a head 1, a flange 2 secured around the head, and a collar or neck 3 within and closely fitting the flange and projecting outwardly therefrom, forming a shoulder 4. A seal-ripping cord 5' extends from the shoulder, being secured between the collar and the flange, and of sufficient length to lie along the shoulder beneath a seal or label strip which may fasten a top to the box. Upon 25 pulling the cord the seal is broken and the top may be turned back or removed. In the present embodiment the flange and the collar are each formed from blanks of superposed materials, and the flange and the collar are similar in several respects, as will appear.

In forming the collar a body strip or blank 5 of relatively thick paper, is provided, and its sides are preferably beveled or scarfed on opposite faces of the blank, and apart from or outside the folding lines of the strip, providing two opposite edges as at 6, 6, so that when the beveled portions are superposed and abutted the joint will 40 be of the same thickness as the body material. At the portion of the body strip designed to form the corners of the collar, grooves or scores 7 are made, preferably by removing the material of the body strip by 45 means of rotary emery wheels having beveled or convex edges, so that the grooves have longitudinal walls angularly disposed relatively to each other, more clearly shown at 8, 9 in Fig. 9. Moreover, by forming 50 the grooves in this manner the body material does not have to be pressed to such a degree as might result in a bead or projection on the face of the strip opposite the grooves, which would tend to form a round 55 or curved corner on the outside of the collar when the strip is folded, instead of a relatively square corner, as by the present construction.

A strip of cover material 10 is provided 60 with glue or other suitable adhesive throughout one face, and its glued face is applied against the unscored face of the body strip 5, the strip being of such width as to extend beyond one side edge of the 65 body strip, as at 11, the other side of the

cover strip being closely adjacent the inner edge of the scarf 6 at the other side of the body strip 5, as at 12. The body strip 5 is of such length, or depth, as may be required for the collar, its rear edge being 70 flush with the rear edge 13 of the cover strip, and the front edge of the cover strip extends forwardly of the front edge 14 of the body strip so that it may be folded around the front edge of the body strip 75 and adhesively secured to the scored face thereof, across the scores 7, as at 15. The cover material is preferably glazed on the face which forms the outside of the collar, and is of thinner material than the body 80 material, and when the two strips are assembled as stated, the cover provides a smooth ornamental surface for the collar. The cover strip is slit from its front edge to the edge of the body strip, as at 16, the 85 slit being located at such a point as to provide a tongue 17 opposite the scarfed portion. In forming the collar the extended portion of the cover strip to the left of the slit 16, in Fig. 1, is folded over the 90 front edge of the body strip, the tongue 17 being unfolded; then the assembled blanks are folded at the scores into a continuous angular element, preferably a rectangular collar, the scores being on the inside at the corners, and the scarfs or edges 95 6, 6, are overlapped and abutted, with the interposition of adhesive to secure the scarfed joint, the forward edges being in parallel relation. The disposition of the scores and 100 relative width of the blank sections between the scores is such that the scarfed joint will assume a position about midway the length of a side of the collar between two adjacent folding lines, as in Fig. 4, the scores 105 being located at the corners. Thus the cover strip will be in position folded over that edge of the body strip which is transverse to the abutting edges 6, 6. Then the tongue 17, which will now be located opposite the joint formed by the abutting edges 6, 6, is folded over the edge of the collar and against the inside thereof, being secured by the adhesive on the tongue. The 110 tongue is of sufficient width to cover, when folded, the scarfed joint opposite thereto, and extend at either side of said joint and overlap the opposite side of the cover strip, thus concealing the body strip on the outside at the joint, and also covering the joint 115 to a considerable depth on the inside of the collar, the inner side 17' of the tongue being, in this embodiment, intermediate the side edge of the body strip and the adjacent groove or folding line of the body strip. 120 When the strips are folded the walls of the grooves 7 approach each other, and those portions of the cover strip facing the grooves are deflected toward the grooves and preferably thereinto so as to avoid bunching of 125 130

the cover strip at the corners, the walls of the grooves in the completed collar being preferably spaced sufficiently to receive the cover strip, as shown in Fig. 9. Thus a 5 relatively square or sharp corner is formed on the inside and outside of the collar, the cover material on the inside being smoothly disposed at the corners. A collar formed in the manner related is shown in Fig. 5, individual steps in its formation being shown 10 in Figs. 1, 2, 3 and 4.

In case a container or box is to be made, a flange is made in a manner like that of the collar, but in the case of a flange it is preferred to utilize the cover strip to secure the head to the flange. In this case the cover strip is extended rearwardly as well as forwardly of the body strip, as at 18, Fig. 6, the extension being also covered on the inner 15 side with adhesive. A head is then applied with one edge against the rear part of an intermediate section of the body strip of the flange and with its corners adjacent the two inner grooves 7. Then the flange is folded 20 around the head, the corners of the head enter the grooves in the flange, and the overlapping or beveled joint of the flange is formed in the same way as explained for the collar. The rear extension of the cover 25 strip in this embodiment, however, will extend below the head and is folded over against the head on each side and adhesively secured thereto, fastening the head and flange together. A box body formed in this manner is illustrated in Fig. 12, and embodies 30 all the features of the collar except the flush edge of cover strip and body strip.

When a box having a collar or neck is to be produced, the collar is preferably formed 40 separately from the box body, but each in the manner above described, the collar being of a size to closely fit within the flange of the box body, and these elements are assembled by sliding or telescoping the one with the other, resulting in the box illustrated in Fig. 45 8. Owing to the relatively square corner on the inside of the flange, the relatively square outside corners of the collar fit nicely at the corners of the flange, the cover strip of the 50 collar closely fitting the folded portion of the flange cover, which latter is smooth at the grooved corner as explained in connection with the collar, and it will be noted that by the smooth disposition of the cover strip 55 on the inside of the flange, the collar may readily slide into position, there being no bunches or protrusions of the flange cover to be torn or rumpled, or which might tend to tear or ruff up the collar cover on the outside. Suitable adhesive is placed around the 60 peripheral walls of the box on the inside opposite the collar, to secure the collar in the flange, and one end of the ripping cord 4 is inserted between the collar and the flange 65 and in contact with the adhesive, whereby

the collar, the flange and the cord are efficiently connected. The relative disposition of the elements of the box having a collar and a cord is illustrated in section in Fig. 9. The joint in the collar or the flange may be 70 located at one corner of either of said elements, if desired, without detracting from the efficiency of the construction. For example, in Fig. 10 is illustrated a collar blank having the grooves so disposed that when 75 the blank is folded in the manner previously explained, the sides of the body strip meet, the edge of one side abutting the inside face of the other side and the body strip having no scarfs at its sides. The cover strip at one 80 side is slotted in line with or slightly beyond the side edge of the body strip, as shown at 19, and the side of the cover strip is extended, as at 20, to provide sufficient material to cover the exposed body material and 85 overlap the other side of the cover strip when the blank is folded, as illustrated in Fig. 11. It is obvious that the box body of Fig. 12 may have the joint formed at the corner in the same manner as illustrated in Fig. 11 90 without departing from the invention.

The construction described is found extraordinarily efficient when embodied in flexible boxes or elements made of flexible and relatively soft material, as referred to, 95 and when the boxes or elements are made automatically, as, for instance, by the machine described in the prior application, the construction described offers special advantages whereby the product is efficient and not 100 liable to be defaced or destroyed while being made.

As many changes could be made in the above construction and many apparently widely different embodiments of this invention could be made without departing from the scope thereof, it is intended that all matter contained in the above description or 105 shown in the accompanying drawings shall be interpreted as illustrative and not in a 110 limiting sense.

Having described my invention, what I claim as new and desire to secure by Letters Patent is:—

1. A box comprising, in combination, a 115 polygonal flange having grooves on the inside at the corners, and a polygonal collar the corners of which engage the grooves in the flange.

2. A box comprising, in combination, a 120 polygonal flange having grooves on the inside at the corners, a polygonal collar, and a head, the corners of each of which latter engage the grooves in the flange.

3. A box comprising, in combination, a 125 polygonal flange having grooves on the inside at the corners spanned by a strip of cover material, a covered polygonal collar the corners of which are disposed opposite the grooves of the flange, the cover of the 130

collar being adjacent the cover strip of the flange, and a head the corners of which lie in the grooves of the flange.

4. In combination, in a box, a polygonal flange comprising a body strip having material removed on the inside at the corners, a cover strip adhesively secured to the outside of the body strip extending over the edge thereof and adhesively secured to the inside thereof, a polygonal collar adhesively connected to the flange and comprising a collar body strip having material removed on the inside at the corners, and a collar cover strip adhesively secured to the outside of the collar body strip extending over the edge thereof and adhesively secured to the inside thereof, the corners of the collar engaging the grooves at the corners of the flange.
5. An article of manufacture comprising, in combination, a body strip comprising beveled side portions, said strip adapted to be folded and its beveled portions superposed, and a foldable cover strip on the body strip having a forwardly projecting tongue the inner side of the tongue being intermediate the side of the body strip and the adjacent folding line.
6. An article of manufacture comprising, in combination, a body strip adapted to be folded on predetermined lines into a continuous box element, said strip having its side portions beveled outside the folding lines, said beveled portions being superposed in the folded element, and a foldable cover strip on the body strip having a forwardly projecting tongue, the inner side of the tongue being intermediate the side of the body strip and the adjacent folding line.
7. A box comprising, in combination, a polygonal flange having grooves on the inside at the corners, and a polygonal covered

collar within the flange, the corners of said collar engaging the grooves of said flange, said collar comprising a folded body strip the opposite edges of which abut each other at a point between two adjacent grooves and beneath the cover, the cover material lying over the peripheral edge of the collar.

8. A continuous angular box element comprising, in combination, a body strip folded so that two opposite edges abut each other between two adjacent folding lines, and a cover strip adhesively attached to said body strip and folded over that edge of the body strip which is transverse to said abutting edges, said cover strip being slit transversely of said transverse edge at a point to one side of said abutting edges, thereby providing a folded tongue opposite the joint formed by said abutting edges, said tongue extending at either side of said joint, and adhesively secured in position.

9. A continuous angular box element comprising, in combination, a body strip folded so that two opposite edges overlap each other between two adjacent folding lines, and a cover strip adhesively attached to said body strip and folded over the parallel edges of the overlapped portion of the body strip, said cover strip being slit transversely of said parallel edges at a point to one side of said overlapped portions and between the adjacent folding lines, thereby providing a folded tongue opposite the joint formed by said overlapped portions, said tongue being adhesively secured in folded position.

In testimony whereof I affix my signature, in the presence of two witnesses.

CARLOS HOLLY.
